7 Claims. (Cl. 114—16)

The present invention relates to submarine machines i.e. to machines immersed in water.

We will first remind some data relative to the problems of machines intended to be used under water. Such machines generally consist of two portions having distinct functions, to wit on the one hand the cabin for the crew and the control means, the inside of this cabin being kept at atmospheric pressure whatever be the external hydrostatic pressure (the walls of this cabin are therefore sufficiently thick to be able to resist the action of compression forces from the surrounding medium so that, in most cases, the apparent density of this portion is much higher than that of water) and, on the other hand, a float divided into compartments intended to work as water ballasts and to compensate for the excess of weight of the first portion. This result is obtained by filling said compartments with a body or bodies of a density lower than that of water. Gases and liquids are mostly utilized to constitute said bodies. However, the use of such fluids involves conditions corresponding essentially to their physical behaviour. As a matter of fact, these lift producing fluids are, as a rule, generally more compressible than water. Consequently when the machine sinks deeper and deeper into water, the volume of a given mass of such a fluid decreases more than that of the same mass of water considered at the same depth. The result is an apparent increase of the weight of the machine due to a reduction of the archimedean thrust. In known submarine machines intended to work at great depth, this phenomenon is compensated for in various manners. In bathyscaphes, ballast is released as the depth increases. Without this reduction of weight, the machine would move downwardly with a uniformly accelerated movement which would be braked only by friction forces. In so-called "Aquarius" apparatus, which use a gas as sustaining fluid, the gaseous volume is kept substantially constant by constantly adding further gaseous masses. Considering either of these apparatus in equilibrium in water, at a given depth, any displacement from the position of equilibrium will tend to become greater and greater. In other words the equilibrium is unstable.

The object of the present invention is to obviate these drawbacks and to provide a machine of the above mentioned type which is kept in stable equilibrium without making use of any external force.

For this purpose, the upward force is obtained at least partly by means of bodies in the solid state, the specific mass and compressibility of which are lower than the respective specific mass and compressibility of the surrounding liquid medium, i.e. water.

It can be shown that, in this case, the equilibrium of the machine is stable. This can be easily understood by supposing that the compressibility of the sustaining bodies is negligible. From the point of view of the actions exerted thereon, the machine in equilibrium in the liquid is then equivalent to an equal volume of the liquid present in the zone occupied by the machine and this zone is located between a denser zone located below it and a lighter zone located above it. If, for instance, the machine is moved upwardly into the upper zone, its weight becomes

2

higher than the thrust acting thereon and the result tends to bring it back into its initial position. A similar result would be produced if the machine were moved into the lower zone.

5 The machine according to this invention may have the following characteristics, taken either separately or in different combinations:

(a) The sustaining bodies are non porous solids or solids provided with small holes therein, without communication between these holes, the solubility of said solids in water being negligible;

(b) The sustaining bodies are solids coated with a suitable substance which may be varnish, paint, or a metal coating, or disposed in a sheath of thin plastic material, in order to prevent direct contact with the surrounding liquid, i.e. water;

(c) The sustaining bodies are fluidtight hollow solids containing a fluid, and more especially a gas, under pressure;

20 (d) The sustaining bodies are hollow solids having hooped walls.

The arrangements mentioned at (c) and (d) are intended to improve, by hooping or by production of an internal counter-pressure, the resistance of the hollow bodies to the external hydrostatic pressure.

25 It is known that there are many substances that can be used for making at an acceptable price sustaining bodies corresponding to the above characteristics.

30 By way of non limitative example we may cite long chain saturated hydrocarbons and some of their acids, nitriles and ketones. One of the most known of these is stearic acid. However this substance is not the most favorable because it is very slightly soluble in water. Furthermore its density is relatively high, being 0.847.

35 On the contrary the corresponding saturated hydrocarbon, octodecane, is not soluble in water and its density is only 0.7768. Triphenylamine, of a density of 0.774, can also be used.

40 The use of hollow or alveolar bodies makes it possible to obtain, from heavy materials such as metals, sustaining bodies of very low apparent density. Of course the mechanical properties of the material forming the walls of said bodies must be sufficient to enable the recesses both to resist the compression and to have walls thin enough 45 to permit of obtaining a low density. This last condition therefore implies a maximum rate of filling of the recesses. This rate may be determined in the following manner; if d is the density of the surrounding liquid medium (water) and D that of the material of which the walls of the bodies are made and if V_i and V_e are respectively the internal and the external volume of the body, said body has a positive floatability if:

$$55 d > \left(1 - \frac{V_i}{V_e}\right) D$$

60 The floatability is the greater as the first member of the above inequality exceeds the second member. Mechanical considerations supply the lower limits below which the thickness of the walls must not decrease. From this point of view it seems preferable, at the present time, to use a hollow sphere, which has a geometrical shape well adapted to resist compression. The risks of breaking of the body appear when the tension supported by the wall is equal to or higher than the elastic limit of the material. It is therefore necessary to use the material below this limit. The tension t on the inner wall of a sphere subjected to an external uniform pressure P is given, according to Lamé, by the following formula:

$$70 t = P \frac{3R^3}{2(R^3 - r^3)}$$

wherein R and r are the external and internal radii of the sphere, respectively. In the case of a sphere made of steel, the physical characteristics of which are as follows: density 7.7, yield point 80 kg./mm.², it is possible to arrange so that the material works under tensions lower than or equal to 25 kg./mm.², in order to have a sufficient safety margin. In these conditions, with an external pressure averaging 100 kg./cm.², the Lamé formula indicates that the ratio of the radii must be equal to 1.021. The resulting density is 0.462. The sustaining power of such spheres is therefore much higher than that of solids. It is possible to reach higher sustaining powers by making use of materials of lower density but having good mechanical characteristics. For instance, with glass, in the same conditions of utilization, the density will be only 0.138.

Of course, the spherical shape is not the only one that can be used according to our invention.

According to the present invention it is possible further to increase the resistance to external pressure of the hollow bodies that are used without considerably increasing their apparent density by filling the recesses with a fluid under pressure and in particular with a gas under pressure. For instance the internal pressure in the hollow body will be one half of the hydrostatic pressure.

By proceeding in this manner, it is possible to reduce by nearly one half the value of the apparent density of the hollow body. Of course the fluid that is used must have a density as low as possible. By way of non limitative example we may operate as follows: A glass tube, one of the ends of which is initially closed, is cooled in liquid nitrogen. It is subsequently partly filled with a certain amount of a liquefied gas and the tube is finally sealed. The gas thus imprisoned in the glass tube creates, at normal temperature, the desired pressure. The thickness necessary for the walls of the tube can easily be calculated by means of the Lamé formula. Concerning the sealing of the free end of the tube, it constitutes an operation without special difficulties for someone skilled in the art.

It is interesting to note here the interest, from the point of view of safety, of using a highly divided ballast such as obtained by the use of hollow bodies according to the present invention. The risks of accident resulting from shocks or mechanical accidents are greatly reduced.

Of course the present invention comprises the adaptation to existing machines of sustaining device using as active elements solid bodies such as above specified, which may replace more or less the sustaining means used prior to this invention. To be more definite, the invention is concerned with a submarine machine wherein the float, either divided or not into compartments, contains a multiplicity of solid sustaining bodies as above specified, said machine being possibly further characterized by at least one of the following points:

(a) The machine comprises a compressor plant making it possible to force a gas under pressure into at least one compartment so as to drive out water therefrom and which may work in the reverse manner when it is desired to extract the gas from said compartment and to fill said compartment with water;

(b) The machine comprises a special compartment giving it a complete automaticity for its vertical displacements;

(c) The machine is provided with weights which can be dropped either separately or at a single time;

(d) The machine is provided with a propelling device for horizontal displacement;

(e) The machine is fitted with auxiliary means for performing various works during immersion.

A preferred embodiment of our invention will be hereinafter described with reference to the appended drawings, given merely by way of example, and in which:

FIG. 1 diagrammatically shows, in vertical section, a machine according to the present invention;

FIG. 2 diagrammatically shows the gas circuit of the machine of FIG. 1;

FIG. 3 is an axial section of a hollow body used according to the present invention.

The machine according to FIG. 1 comprises a cabin 1, with thick walls capable of resisting the external liquid pressure, supported by a float 2 divided by walls 3 into compartments 4, 5, 6, 7, 8, 9, 10, 11, 12. The division of this float into compartments facilitates the balancing of the machine and improves safety in case of shocks. The compartments in question each contain a suitable amount of solid sustaining bodies 31. Each of the float compartments 4, 5, 6, 7, 9, 10, 11 and 12 contain solid sustaining bodies 31. However these bodies 31 do not fill up the above mentioned compartments but leave some free space therein, which can be occupied either by water entering through holes 32 provided in the lower walls thereof (the dimensions of said holes 32 being of course smaller than those of bodies 31 so that said bodies cannot escape from the above mentioned compartments through said holes 32) or by a gas under pressure supplied as it will be hereinafter described. This arrangement permits of obtaining an important upward force when water is replaced by gas under pressure. The reserve of this gas is placed in containers 13 and 13_a connected through the circuit shown by FIG. 2 with the central chamber or compartment 8. This circuit comprises in particular a compressor 14 adapted to work in both directions, that is to say capable of transferring gas from containers 13 into compartment 8 and inversely from compartment 8 into containers 13 and 13_a. The gas circuit has been shown for compartment 8 but of course similar circuits may exist between containers 13 and 13_a and compartments 4, 5, 6, 7, 9, 10, 11 and 12.

For the sake of safety, the machine further includes weights placed in boxes 15 fixed to cabin 1 and which can be dropped separately.

Horizontal propulsion of the machine is obtained by means diagrammatically shown at 16.

The central compartment 8, which is provided at the bottom thereof with communications with compartments 7 and 9 in addition to its use to control the vertical displacement of the machine further serves as communication with cabin 1. For this purpose it is fitted with closing means diagrammatically indicated at 17 and 18.

Finally cabin 1 is provided with windows 19 and 20 for guiding the machine and observing the surrounding medium.

We will now describe with reference to FIG. 2 the gaseous circuit for controlling the vertical displacements of the machine by transfer of gas between containers 13 and 13_a on the one hand and compartment 8 on the other hand. Gas transfer is obtained by means of compressor 14 driven by its engine 21.

Pressure gauges 22 and 23 measure the pressures existing respectively in containers 13 and 13_a and in compartment 8. For instance, the vertical displacement velocity may vary according to a given law, or the depth at which the machine is under the surface of water may be kept constant or substantially so. Valves 24, 25, 26 and 27 permit of establishing the desired circuits with compartment 8. For instance when it is desired to discharge gas into this compartment, valves 24 and 26 are opened whereas valves 25 and 27 are closed. At 28 and 29 we have shown two valves connecting compressor 14 and gas containers 13 and 13_a with a distributing machine 30 for sending gas to the other compartments.

FIG. 3 is a sectional view of a hollow body made of cylindrical portions 33 and 34 shrunk on each other and semi-spherical end portions 35.

In a general manner, while we have, in the above description, disclosed what we deem to be a practical and efficient embodiment of the invention, it should be well understood that we do not wish to be limited thereto as there might be changes made in the arrangement, disposition and form of the parts without departing from the principle of the present invention as comprehended within the scope of the appended claims.

What we claim is:

1. A submarine machine comprising a frame and a fixed number of sustaining bodies at least the outer wall of which is solid and uninterrupted, said bodies being operatively connected with said frame to transmit thereto an upward thrust, the specific gravity of said bodies being less than 1 and their compressibility being less than that of water, the number of said bodies being such that the total upward thrust they exert in water on said frame is equal to at least a substantial portion of the total apparent weight in water of the remainder of said machine.

2. A machine according to claim 1 wherein said bodies are made of a non porous solid substance.

3. A machine according to claim 1 wherein said bodies are made of a solid substance having a multiplicity of non communicating cavities therein.

4. A machine according to claim 1 wherein said bodies consist of a solid substance and a watertight coating surrounding said substance.

5. A machine according to claim 1 wherein said bodies are hollow solid bodies.

6. A machine according to claim 1 wherein said bodies are hollow solid bodies filled with a gas under pressure.

7. A submarine machine which comprises, a frame, a float rigid with said frame comprising a plurality of compartments, at least some of said compartments being

provided, at the bottom thereof, with openings placing the inside thereof in communication with the outside, a cabin, a fixed number of sustaining bodies in said last mentioned float compartments, at least the outer walls of each of bodies being solid and uninterrupted, the specific gravity of said bodies being less than 1 and their compressibility being less than that of water, the number of said bodies being such that the total upward thrust they exert in water on said float is equal to a substantial portion of the total apparent weight in water of the remainder of said machine, and means carried by said frame for driving a gas into at least some of said compartments to expel water therefrom.
